UNITED STATES PATENT OFFICE

BODNEY S. PULLEN, OF PHILADELPHIA, AND WILLIAM J. CROWELL, JR., OF WYNCOTE, PENNSYLVANIA, ASSIGNEES TO PULLENLITE COMPANY, OF PHILADELPHIA, PENNSYLVANIA, A CORPORATION OF PENNSYLVANIA

FEED FOR MATCH PACKAGING MACHINES

Application filed February 21, 1930. Serial No. 430,216.

Our invention relates to mechanism for delivering matches from a hopper to one or more conveyor blocks or to one or more match packets.

- 5 A purpose of our invention is to provide efficient mechanism of the character indicated that will be easy and inexpensive to manufacture and well adapted to meet the needs of service.
- 10 A further purpose is to provide a match hopper having guiding delivery grooves at the bottom of the hopper with one or more oscillating wall members parallel to the matches and preferably having opposing members oscillating in opposite directions, the oscillation being either rectilinear or angular.
- 15 A further purpose is to laterally oscillate one or more rods in the interior of a hopper of the character indicated, making the rods generally parallel to the matches thereof and the oscillation along a path or paths that individually may be either rectilinear or curved and that may or may not be endless.
- 20 A further purpose is to use an auxiliary hopper and auxiliary push rods in order to insure against misses in the matches of one or more charged conveyor blocks or one or more packet wraps charged with matches, the blocks or wraps being initially charged in any suitable way as by means of a first hopper and push rods.

We use the presence of the individual matches in a charged conveyor block or a charged packet wrap to determine the non-operation of individual charging rods at an auxiliary hopper, providing means whereby the rods at the auxiliary hopper operate at any missed divisions of the presented block or packet wrap and do not operate at the divisions already containing matches.

Further purposes will appear in the specification and in the claims.

We have elected to illustrate one main form only of our invention, showing however a detail modification and selecting a main form and modification that are practical and efficient in operation and which well illustrate the principles involved.

Figure 1 is a fragmentary and somewhat

diagrammatic plan view illustrating a desirable embodiment of our invention, the view corresponding to a horizontal section taken upon the line 1—1 of Figure 2.

Figure 2 is a partly sectioned front elevation of Figure 1.

Figures 3 and 4 are vertical sections of Figure 1 respectively taken upon the lines 3—3 and 4—4 thereof.

Figure 5 is a vertical section corresponding to a fragment of Figure 4 but showing a detail modification.

Figure 6 is a detail section to enlarged scale taken upon the line 6—6 of Figure 4.

Figure 7 is a section of Figure 6 taken upon the line 7—7 thereof.

Figure 8 is a diagrammatic view corresponding generally to Figure 3 but illustrating a form different from that shown in Figure 3, Figures 1 to 3 showing the matches delivering from a plurality of hoppers to conveyor blocks for subsequent delivery at a subsequent position of the blocks into a plurality of match packet wraps while Figure 8 shows the matches as delivering directly from the hopper into a plurality of packet blanks.

Figures 9 and 10 are detail sections taken upon the line 9—9 and 10—10 respectively of Figure 8.

Figure 11 is a fragmentary right end elevation of Figure 1.

Figure 12 is a vertical section of Figure 1 taken upon the line 12—12 thereof.

Figures 13 and 14 are fragmentary vertical sections corresponding to fragments of Figures 3 and 4 respectively and illustrating a form of our match delivery mechanism that differs somewhat from that shown in Figures 3 and 4 and is particularly advantageous.

Figures 15 and 16 are vertical and horizontal sections of Figure 13 taken respectively upon the lines 15—15 and 16—16 thereof, some of the parts shown in Figure 13 being omitted in Figure 16.

Describing in illustration and not in limitation and referring to the drawings:—

Our invention is believed to have its widest application in automatic match packeting.

machines, usually relating specifically to mechanism for a match delivery that may be either directly into the wrap portions of match packets or into conveyor blocks for subsequent delivery to wraps.

In the embodiment of our invention illustrated in Figures 1 to 4, we show mechanism for match delivery to the successive blocks of a conveyor, each forward stroke of a delivery plunger simultaneously operating on six successively adjacent blocks, charging matches into the first three blocks and at the next three operating upon blocks intended to have been fully charged with matches by the preceding stroke of the plunger, putting in matches at any place or places missed by the preceding stroke.

The conveyor 15 of any suitable length comprises a succession of match receiving blocks 16 that are mounted on or form the successive links of a sprocket chain, the chain passing over suitable guide wheels not shown, along a suitable stationary guide 17 and being intermittently progressed along the guideway by a mutilated gear 18 which presents teeth 19 to downwardly presented teeth 20 on the blocks 16.

The shaft 21 is journaled in suitable bearings 22 and driven continuously in any suitable way, as from a pulley 23 by a belt 24. It is shown extending transversely to the line of travel of the conveyor, and carrying a mitre gear 25, a drum cam 26 and a bevel gear 27.

The gear 27 meshes with a gear 28 on a shaft 29 that may desirably comprise a main operating cam shaft of the packeting machine, not shown.

The drum cam 26 reciprocates a match delivery plunger 30, an endless slot 31 around the drum receiving a suitable roller 32 mounted upon the end of a suitable arm 33 rigidly fastened to the plunger through a plate 34. The plate is adapted to reciprocate in a guiding slot 35 of the stationary frame structure 36 of the machine, so that each rotation of the shaft 21 reciprocates the plunger 30 in a manner determined by the path of the slot 31.

The mitre gear 25 meshes with a gear 37 upon a shaft 38 which is mounted in suitable bearings 39 and carries a circumferentially slotted drum 40 and a bevel gear 41.

The drum 40 is provided with a succession of longitudinally spaced circumferential cam grooves 42 which receive the downwardly presented edges of levers 43 used to determine the operation of mechanism for filling any missed spaces with matches.

The bevel gear 41 (Figures 2 and 11) at the end of the shaft 38 meshes with a gear 44 upon the lower end of a vertical shaft 45 which operates stirring mechanism in the match hoppers, the shaft being journaled at 46, gearing at 47 with a horizontal shaft 48 that is journaled at 49 and is geared at 50 and

51 to the shafts 52 and 53 respectively along the front and back of the match hoppers 54.

The conveyor receives an intermittent movement from the mutilated gear mechanism which is dimensioned so that each forward movement of the conveyor has a length equal to that of three match block units side by side.

The match block units 16 of the conveyor are guided by stationary frame structure 17 horizontally across the line of discharge from the six match hoppers and at the end of each forward movement of the conveyor, the blocks 56, 57 and 58 registering with hopper sections 59, 60 and 61, are empty while the blocks 62, 63 and 64 registering with the hopper sections 65, 66 and 67 have just been stepped forward from registry with the first three hopper sections and presumably and normally are now fully charged with matches received from the first hoppers during the preceding rest period.

Abnormally, however, each of the 62, 63 and 64 blocks may now be lacking any one or any number of its matches due to a miss or incomplete functioning of the charging operation during the last period of rest.

During the rest period, the first three successive blocks receive a charge of matches from the bottom of the first three match hopper sections while the second set of three successive blocks receive any make-up matches needed incident to any incomplete functioning of charging mechanism while the blocks were at the first three hopper sections during the preceding rest period.

The match hopper sections are all alike and successively separated by thin partitions 68 of the composite hopper.

Each hopper section has an inside length 105 from front to rear slightly greater than that of the matches 69 and therefore about equal to the front-to-rear dimension of the individual match blocks of the conveyor.

The bottom of each hopper section comprises a row of upwardly grooved seats 70 for matches, the depth of the grooves being such as to adapt them to hold a plurality of matches one on top of another and the width of the grooves adequate for easy seating of a single match and too narrow for the presence of more than one match laterally in any groove.

The matches present their head ends toward the conveyor blocks.

The front wall 71 of all the hoppers is provided with a row of discharge openings 72 in front of the heads of the bottom matches in the groove seats 70 while a corresponding row of push rod openings 73 in the back wall 74 at the stick ends of the bottom matches affords a guiding entry for push rods 75 into the bottoms of the individual groove seats 70.

The push rods 75 of the first three hoppers 130

continuously longitudinally interlock with the plunger 30, a downwardly directed rectangular notch 76 on the bottom of each push rod near the rear end thereof fitting over an upwardly directed lug or key 77 of the plunger. All the rods are slid forward by each forward stroke of the plunger so that the forward end of each rod pushing a match ahead of it traverses its groove 70 to a position beyond the hopper at the rearward end of the alined groove seat 78 of the conveyor block 16, the return stroke of the plunger and of all the push rods leaving the matches in the alined grooves 78 of the conveyor block.

Each push rod 75 has a square end 79 too small to engage more than one match stick end when it enters the groove 70.

The plunger 30 and push rods 75 operate between stationary horizontal plates 81 and 82 that form part of the stationary frame structure of the machine.

The upper plate 81 forms a cover for the plunger and push rods, being upwardly grooved at 83 rearwardly from its forward edge to receive and guide the push rods and is suitably fastened to the lower plate.

The lower plate 82 comprises a forward portion 17 machined to guide the conveyor blocks 16, and intermediate portion forming the bottom of the hoppers and a rearward portion 84 that guides and supports the plunger 30.

The lower plate is downwardly grooved at 70 to provide the groove seats for the matches, is downwardly recessed rearwardly thereof at 85 to provide a guiding seat for the body of the plunger 30 and vertically slotted to 35 to pass and guide the plate 34 that makes operative connection with the drum cam 26.

The longitudinally interlocking connection between the operating plunger 30 and the push rods may be made in any one of a number of different ways of which I have shown two only for the push rods operating at the first set of hoppers, illustrated in Figures 3 and 13 to 16 and three only for the push rods operating at the second set of hoppers, illustrated in Figures 4, 8 and 13-16 inclusive.

In Figure 3 the plunger 30 is provided with upwardly projecting lugs 77 spaced along the forward edge of the plunger, each lug registering with a downwardly directed notch 76 of one of the push rods and having a thickness along front of the plate substantially that of the push rods.

With this arrangement, the downwardly directed grooves 83 in the upper plate 81 have guiding walls between the successive push rods that may extend downwardly to the bottom of the push rods, the push rods being loosely supported at front and rear respectively upon the rearward ends of the

individual groove seats 70 and upon the forward end of the plunger 30, and reciprocating every time the plunger reciprocates.

The longitudinal interlocking illustrated in Figures 13 to 16 inclusive is almost the same as in Figure 3 except that a continuous upwardly directed key or feather 77' is provided along but somewhat inwardly from the front edge of the portion of the plunger 30 that lies directly back of the first three hoppers.

As before, the push rods present downwardly directed notches 76' over the upward projection from the plunger and are continuously supported at their forward ends in the grooves 70.

As the key or feather 77' is continuous the bottom portions of the walls of the grooves 83 in the upper plate 81 are cut sufficiently to permit key or feather to reciprocate below these walls that is (Figure 13) to the dotted line 86 which indicates the bottom line of the walls between the grooves that guide the push rods.

Any longitudinal interlocking between the plunger 30 and one or more of the push rods 87 of the last three hoppers only takes place in the event of a miss delivery at one or more of the plungers of the first three hoppers and we provide any suitable form of latching connection between the plungers and push rods that is adapted to be made effective by the mere absence of a match or matches in the blocks when they are presented in charging position at the second set of hoppers.

In Figures 4 and 8 the plunger 30 is provided with forwardly directed fingers 88 or 88' that press resiliently downward and are each provided with an upwardly projecting toe 89 or 89' that is adapted to seat in a downwardly directed recess 90 or 90' of the push rod.

The fingers have hinge connection at 91 or 91' with the body of the plunger, the fingers being shown as an integral portion of the plunger in Figure 8 and as separate members from the plunger in Figure 4.

In the construction of Figures 8 and 9 the fingers are formed by suitably cutting away the metal at 92 intermediate the fingers and at 93 at the roots of the fingers to form thin resilient hinge connections 91' between the body of the plungers and the individual fingers.

The forward portions of the fingers are given a slight downward set so that the toes 89' if free to do so spring downward far enough to clear the front wall 94 of the recess 90'.

We cut away the lower edge of the wall 94 and provide rearwardly downwardly sloping grooves 95 for the individual fingers so that in retracted position the forward ends of the fingers normally press down into the sloping grooves and as the plunger moves

120

125

130

forward from its retracted position the toe 89' will normally ride up the slope of the groove 95 under the lower edge of the wall 94 to rise in front of the wall after it has passed the wall into a groove 96 cut upwardly in the bottom of each finger forwardly of the wall 94.

On the return stroke the toe 89' slides down the slope of the groove 95 thus avoiding engagement with the wall 94.

Each finger thus normally reciprocates along the groove 95 without touching the push rod, the toe 89' of the finger extending up into the groove 96 of the push rod during the forward portion of the stroke but sinking at the rear end of the stroke sufficiently to miss the wall 94.

We downwardly slot the plate 82 at 97 from each of the grooves 95 at portions thereof registering with the finger when the plunger is retracted and mount a series of levers 43, one for each of the fingers 88.

The levers 43 rest side by side in the cam slots 42 along the drum 40, extend forwardly under the conveyor blocks to hook upwardly over the individual groove seats 78 of the conveyor blocks 62, 63 and 64, and extend rearwardly and then upwardly at 98 into the slots 97.

The forward ends of the levers 43 are pulled resiliently downward by individual springs 99 and some distance rearwardly of the drum 40 the upper edges of the levers make individual loose notch connection with the bottom and preferably upwardly notched edge of a plate 100 fastened transversely across the tops of the levers to the bottom of the plate 82.

The forward ends 101 of the levers are desirably registered exactly above the groove match seats 78 of the conveyor blocks by a suitable stationary guide 102 fastened in any suitable way to the frame structure of the machine.

The levers loosely pivot continuously upon the bottoms of the cam grooves in the drum 40 with the forward ends of the levers pulling resiliently downward under the action of the springs 99.

The dimensions and timing of the cam and lever are so selected that when the plunger 30 begins its forward stroke low portions of cam grooves 42 are presented against the bottom edges of the levers and downward tipping of the forward ends of the levers are limited by an engagement between the bottom edges of the hook portions 101 with either the forward ends of the matches in the grooves 78 of the conveyor blocks or with the bottoms of these grooves.

The position of the rear end 98 of any lever is in the one case too low to engage the bottom of the downwardly sprung finger 88 and in the other case high enough to engage and raise the finger 88 so that the toe thereof

is back of the front wall 94 of the recess 90, thereby effecting operative engagement between the toe 89 and the push rod 75 during the ensuing stroke of the plunger 30 to feed a match into the empty groove of the conveyor block.

After the forward stroke of the plunger 30 has progressed forwardly sufficiently to support the finger in its raised position by reason of its engagement with a forward portion of the bottom of the groove 95, the cam member 40 raises the forward ends of all the levers with a resultant lifting of the hook ends 101 away from the groove seats 78 of the conveyor blocks and a depression of the rearward ends 98 by reason of a pivotal riding of the upper edges of the levers against the plate 100.

In the structure shown in Figures 14 to 16 the key member 77³ which longitudinally interlocks the plunger to the individual push rods is separate from both the plunger and rod and only put to position for locking the plunger and push rods together in the event of an absence of a match in front of the plunger.

The push rods 75 are upwardly notched at 76 on the under side in registry with rectangular perforations 103 through the stationary plate 82 and also in registry when the plunger is in retracted position with rectangular perforations 104 through the plunger near the front end thereof.

Normally the keys 77³ are down in the perforations 103 through the bottom plate 82, each being supported from dropping down through the perforation by an up-turned end 98 of the lever 43.

As long as the members 77³ are in this position reciprocation of the plunger 30 does not move the push rods, and the presence of the matches in the individual grooves 78 of the conveyor blocks prevent the individual levers from shifting their respective keys 77³ into locking position, which is that illustrated in Figure 14.

When or if a match be absent and the plunger 30 is in retracted position the front end 101 of the corresponding lever 43 moves down to the bottom of the groove 78, the upturned end 98 of the lever lifting the key to the position shown in Figure 14 in which it locks the push rod and plunger together.

When the plunger moves forward the key 77³ is still held in its locking position, the bottom of the key sliding over the upturned end 89' of the lever 43.

As soon as the key passes the forward wall of the perforation 103 through the plate 82 it is prevented from escape and remains in place throughout the reciprocating movement of the plunger and push rod, dropping down to inoperative position when the plunger retracts provided that there is now a match present in the groove 78.

There is some tendency for the forward movement of the plunger to move the push rod forward even when the key is not in place and to prevent this I preferably downwardly notch the rearward ends of the push rods at 105 and provide beveled click members 105' in position to latch into these notches when the push rods are in retracted position, so as to spring press the push rods to their retracted positions.

The click members 105' are spring-pressed downwardly into the notches 105 through suitable perforations 105² in the top of the plate 81, and automatically latch into the beveled notches on the top of the push rods when the push rods are retracted.

The click members thus resiliently press the push rods to their retracted position so that considerable force is necessary before the push rods can be pushed forward, thereby insuring no movement of the push rods unless the key members 77³ are in locking position.

The lower plate member 82 fastens to the stationary frame structure in any suitable way not shown and the upper plate 81 removably fastens to the lower plate, as by suitable screws 107.

When these screws are removed, the upper plate lifts away giving access and easy individual removal of the push rods 75 and of the plunger 30.

The groove seats 70 in the bottoms of the hopper sections have preferably a depth sufficient to hold a plurality of matches, desirably four, one on top of another.

We find it desirable to agitate the matches above the groove seats 70 so that the supply matches may keep feeding into the groove seats and important features of our invention are directed to desirable mechanism for effecting this agitation of the matches in the supply portions of the hopper sections.

We make suitable portions 108 of the side walls of each hopper section slowly reciprocate transversely to the matches either angularly or rectilinearly, and preferably also place in each hopper section one or more rods 109 in vertical planes parallel to the desired match alignments, and give these rods transverse movements either in vertical or horizontal directions for securing a simultaneous agitation and proper alining of the matches.

In the structure shown in Figures 1 to 3 the side wall portions 108 are in mid-positions alined with the side walls of the respective hopper sections, the intermediate members 108 comprising movable portions of the partition walls 68, each of which forms one side wall of two hopper sections.

Each member 108 carries alined pivot pins 110 and 111 journaling respectively in perforations in the front and rear walls 71 and

74 and alined crank pins 112 and 113 that extend from the front and rear ends of the member through suitable arcuate slots in the front and rear walls of the hoppers into endless cam grooves 114 of barrel cams 115 ⁷⁰ and 116 upon the rotating shafts 52 and 53.

These shafts have journal support at 117 and 118 respectively across the front and rear of the hopper sections, are driven from the gearing 50 and 51 as already described, and carry the drum cams 115 and 116 which present the endless cam grooves to the crank pins, thereby slowly rocking the plate members 108 about their pivot pins 110. ⁷⁵

Preferably the cam grooves are formed so that the plates upon opposite sides of any hopper section rock in opposite directions.

In the modified form shown in Figure 5 the plate members 108' are guided to rectilinear movements, as by pin and slot connections 119 and 120 near the top and bottom of each end of the plate with front and rear hopper walls and the plates are laterally reciprocated by pins 121 which project through suitable slots to the endless cam groove of the barrel cam 115' on the shaft 52'. ⁸⁰

The rods 109 are preferably in vertical planes parallel to the matches and have front and rear ends 122 and 123 that pass through suitable slots 124 in the front and rear walls of the hopper to find support in holes 125 of front and rear vertical plates 126 and 127. ⁸⁵

The plates 126 and 127 are transverse to the rods 109, give a bearing support to all of the rods 109 and are each limited to movements in a vertical plane by suitable guides, as by spaced bracket strips 128 fastened above the plates to the end walls of the hopper. ⁹⁰

Each of the plates 126 and 127 carries laterally spaced feet 129 and 130 that ride on suitable cams 131 and 132 on the shafts 52 and 53, which move the plates back and forth and vertically and horizontally either or both, as deemed most desirable. ⁹⁵

It will be seen that the continuously rotating barrel members 115 and 116 simultaneously move the plate members 108 and the rods 109 in the way desired and they thus effectively agitate the matches in the supply portions of the hopper sections in a way to insure proper feed of the matches into the groove seats 70 at the bottoms of the hopper sections. ¹⁰⁰

In the structure thus far described the matches are delivered head ends foremost out of the hoppers into groove seats 78 of 125 conveyor blocks whence they are to be subsequently delivered stick ends foremost into the wraps of match packets.

Optionally we may deliver the matches from the bottoms of the hoppers directly into 130

the wraps of match packets and illustrate this in Figure 8.

In Figure 8 the mechanism for delivering the matches out of the hopper and for agitating the matches above the bottom groove seats 70 may all be in substantial accord with that already described.

In this figure the feet 129 and 130 are shown resting on the radial cams 131 and 132 and presenting downward pins 129' and 130' into endless cam slots 131' and 132' adapted to reciprocate the plates 126 and 127 and therefore the agitating wires 109 both vertically and horizontally.

The matches however are placed with their stick ends toward the delivery side of the hopper so that the push rods engage the heads of the matches and have their engaging ends desirably recessed or cupped slightly at 134 in order to provide better engagement with the match heads.

The delivery openings 72' out of the hopper have to be too small to permit more than a single match stick to enter at a time and yet have to be adapted to pass the match head.

In order to accomplish this we provide a rubber member 135 along the delivery side of the bottom of the hoppers providing openings 72' in registry with the bottoms of the grooves 70, the openings 72' being large enough to permit the entry of single matches but too small for an entry of more than one match at a time.

The rubber delivery portal 135 is shown held to place by a metal plate 136 which is provided with openings 137 in front of and larger than the openings 72' through the rubber.

The wraps may be positioned for receiving the matches as they are delivered by the push rods from the openings 72' in any suitable way, preferably by automatic machinery synchronized with the movements of the conveyor and match delivery mechanism.

In the illustrations we indicate that the wraps 138 are mounted in proper registry by hand upon interchangeable auxiliary blocks 139, three wraps upon each auxiliary block, each of which has the length of three of the conveyor blocks 16'.

The short and long flaps 140 and 141 of the wraps are turned up along the rearward and forward sides of the block with suitable perforations 142 and 143 of the wrap registering across the ends of downwardly directed match guiding grooves 144 on the bottoms of the auxiliary blocks.

The downwardly directed grooved guides 144 replace the rearward portions of the groove seats on the block 16 and are adapted to align and register with upwardly directed short groove seats 78² on the block 16' and also with the match delivery openings 72¹.

It will be seen that the match stick portions between the short and long flap of the wrap

are in the downwardly directed grooves 144 of the member 139, and that the projecting stick end portions are in the upwardly directed grooves of the block, these latter grooves ending forwardly from the long flap 141. 70

We find it advantageous to reciprocate the upper portion of the spaced walls between the groove match seats 70 in the bottoms of the hoppers.

Preferably the lower portion of these walls 75 should have no movement in that they should form stationary guides for the push rods during the reciprocation of these members.

In Figures 6, 7 and 12, we show the lower portions 145 of the walls rigid with the bottom plate 82 and the upper portions 146 adapted to rock upon the lower portions, having tongue and groove connections with the lower portions. 80

The front and rear walls of the hopper are 85 longitudinally slotted at 147 and the rocking members 146 have extensions 149 into the slots.

Pins 150 extend inwardly between the extensions 149 from slide members 151 to angularly position the plates 146. 90

The pins 150 preferably extend inwardly to the inside surfaces of the front and rear walls, have a diameter equal to the spacing between the extensions 149 so that the openings 147 are substantially closed by the pins and the extensions 149, thus preventing any entry of matches into these openings. 95

The slides 151 carrying the pins 150 are longitudinally reciprocated to rock the wall 100 members 146 being limited to longitudinal movement by suitable guide plates 152, presenting hook extensions 153 to undulating cam surfaces 154 on the ends of shafts 52 and 53 and being spring-pulled at 155 in a direction to maintain contact between the hook extensions and the cams. 105

The continual rocking back and forth of the wall members 146 between the seats 70 materially assists in maintaining a proper feed 110 of matches into the groove seats.

An operator places three of the wraps in position upon an auxiliary block as indicated in Figures 8 and 10 and then positions the block upon the three conveyor block units 115 16' that are approaching the first of the match hoppers, preferably adjacent the rearward end of a similar block at the first three hoppers.

Suitable registry pin and socket connections 120 145 between the auxiliary block and the conveyor blocks secure exact registry between the downwardly directed grooves 144 of the auxiliary blocks and the upwardly directed grooves 78² of the three blocks upon which they are temporarily carried. Thus the downwardly directed grooves 144 (Figure 8) presented by the auxiliary blocks between the up-turned flap portions 140 and 141 of the wrap exactly align with upwardly 125 130

directed grooves 78² upon the forward sides of the blocks 16' beyond the up-turned flaps 141 and the wrap perforations 142 and 143 for match threading are respectively across 5 the rearward ends of the grooves 144 and between and across the grooves 144 and 78².

It will be seen that the wraps in sets of three are thus placed first in position to receive the charge of matches from the first 10 three hoppers and then during the next charging stroke of the plunger 30 are in position in front of the second three hoppers to insure that any miss-functioning at the first three hoppers shall be corrected before 15 the wraps finally leave the charging mechanism.

After the auxiliary blocks have passed the second set of hoppers the auxiliary blocks 139 are removed and the wrapping operation completed in any suitable way irrelevant 20 to the present invention.

It will be evident that our invention is suitable not only for detecting vacant spaces and filling matches into spaces from or in 25 which they are to be packaged but also for filling matches into definite packages.

For the purpose of covering both of these conditions we have referred to both of these 30 alike in some of our claims as packaging units or packeting units as the invention evidently is not dependent upon the particular character of the unit into which the match has been deposited.

It will be evident that different kinds of 35 exploring mechanism can be used for the purpose of automatically setting in motion, or freeing from motion, filling mechanism of different character intended to place matches within conveyors or within match packages.

The character of the exploring mechanism will be varied, of course, to suit the type 40 of individual match selecting or feeding mechanism by which the matches are separated out from the mass of matches from which they are fed and will be varied also according to the packaging unit with which it must cooperate at one end of its train and the feeding mechanism which it must set in 45 operation or release from operation at the opposite end of its train.

Our illustration and description of the particular type of match-selecting and match-feeding and space-exploring mechanism has 50 been determined, of course, by the requirements of the statute and is not intended to restrict the invention to them or to any of them.

In view of our invention and disclosure, 55 variations and modifications to meet individual whim or particular need will doubtless become evident to others skilled in the art, to obtain all or part of the benefits of our invention without copying the structure, 60 shown, and we, therefore, claim all such in

so far as they fall within the reasonable spirit and scope of our invention.

Having thus described our invention, what we claim as new and desire to secure by Letters Patent is:

1. In a match delivery hopper, a hopper bottom having a succession of match delivery grooves on its upwardly directed surface, each groove too narrow to hold more than one match laterally, two laterally spaced 75 plates higher than the grooves, each parallel to the grooves and adapted to present a steep side along the sides of matches in the hopper and means for laterally and oppositely oscillating the plates in order to laterally agitate the matches, the simultaneous movements of the respective plates being in relatively opposite directions.

2. In a match delivery hopper, a hopper bottom having a succession of match delivery 85 grooves on its upwardly directed surface, each too narrow to hold more than one match laterally, a plurality of plates higher than the grooves alined parallel to the grooves and dividing a lower portion of the hopper into a plurality of hopper sections, each feeding downwardly into a plurality of the grooves, a pivot support for each plate adapting it to be rocked on a longitudinal axis and means for oppositely rocking the successive plates on the pivots in order to laterally agitate the matches.

3. In a match delivery hopper, a hopper bottom having a succession of match delivery 90 grooves on its upwardly directed surface, 100 each too narrow to hold more than one match laterally, two laterally spaced plates forming parts of opposite sides of the hopper, higher than the grooves and each parallel to the grooves and adapted to present a steep side 105 along the sides of matches in the hopper and means for laterally oscillating the plates in opposite directions in order to laterally agitate the matches.

4. In a match hopper, a hopper bottom having a succession of match delivery grooves on its upwardly directed surface, each too narrow to hold more than one match laterally, a pair of laterally spaced vertical partitions in the hopper parallel to the grooves 110 dividing the hopper into hopper sections, plates in the partitions forming part of the respective division walls each presenting opposite sides to matches of adjoining hopper sections and means for laterally reciprocating the plates in opposite directions in order to laterally agitate the matches in the sections.

5. In a match delivery hopper, a hopper bottom having a succession of match delivery 115 grooves on its upwardly directed surface, each groove too narrow to hold more than one, 120 match laterally, a rod in a portion of the hopper above the grooves and in a vertical 125 plane parallel to the grooves and means for 130

reciprocating the rod in a direction transverse to its length in order to agitate and more perfectly aline the matches in the hopper.

6. In a match delivery hopper, a hopper bottom having a succession of match delivery grooves on its upwardly directed surface, each groove too narrow to hold more than one match laterally, a plurality of rods in the upper portion of the hopper in vertical planes parallel to the groove and means for moving the rods in directions transverse to their lengths in order to agitate the matches above the grooves.
15. 7. In a multi-section match hopper for simultaneously feeding a plurality of match carrying members, a bottom for each section having a succession of match delivery grooves on its upwardly directed surface each too narrow to hold more than one match laterally, alternately high and low wall portions in each section higher and parallel to the grooves and means for rocking the wall portions laterally in order to more effectively feed the matches into the grooves.

8. In a multi-section match hopper for simultaneously feeding a plurality of match carrying members, a bottom of each hopper section having a succession of match delivery grooves on its upwardly directed surface, each groove too narrow to hold more than one match laterally, side wall portions of each section higher and parallel to the grooves, a rod in each section higher and in a vertical plane parallel to the grooves and means for reciprocating the wall portions and the rods in planes perpendicular to the grooves.

9. In match packeting mechanism, a multi-section match hopper including a charging section and a safety section adjacent thereto, bottoms for the sections having a succession of match delivery grooves side by side, an endless intermittently moving match conveyor, successive sections thereof transversely grooved for the matches adapted to come to rest at the rest periods of the conveyor before the hopper sections successively in match delivery registry therewith, a plunger, individual push rods alined with the individual grooves of both hopper sections and adapted to be moved along said grooves by each forward stroke of the plunger to deliver matches from the hopper grooves to the alined grooves of the conveyor and means operative by the presence of matches in the conveyor section grooves when the said section comes to rest in registry with the grooves of the safety hopper section for preventing operative connection between the plunger and the push rods then alined with the said present matches.

10. In match packeting mechanism, a safety hopper having match delivery seats, a conveyor having blocks adapted to come successively to rest before the safety hopper,

match receiving seats on each block alining with the delivery seats of the hopper when the block is at rest in front of the hopper, means operative during a rest period of the conveyor adapted to feed matches from the delivery seats of the hopper into the corresponding receiving seats in registry therewith in combination with other means operative during a rest period of the conveyor by the presence of matches in the individual receiving seats alining with the delivery seats to prevent the operation of the said first means at the receiving grooves already charged with matches.

11. In match packeting mechanism, a charging hopper and a safety hopper adjacent thereto, transversely alined match delivery seats in the hoppers, a conveyor having blocks adapted to come successively to rest before the charging hopper and the safety hopper, match receiving seats on the block alining at rest with the delivery seats of the charging hopper and subsequently alining at rest with delivery seats of the safety hopper, means operative during each rest period of the conveyor adapted to feed matches from the delivery seats of both hoppers to the corresponding receiving seats on the conveyor, and other means operative during each rest period individually at the alined delivery and receiving seats of the safety hopper and conveyor respectively by the presence of matches in the said last receiving seats for preventing the operation of said first means at the said last alined seats.

12. In match packeting mechanism, a safety hopper, match delivery seats therein, an intermittent conveyor, match receiving seats thereon adapted to aline with the delivery seats of the hopper during a rest period of the conveyor, push rods rearwardly alined with the delivery seats and adapted to slide therealong for delivering matches therefrom to the receiving seats alined therewith, a plunger having a forward and rearward range of movement in the direction of the seats, a latch for each push rod adapted to lock the rearward end of the push rod to the plunger when the plunger is retracted, rocker members for the individual push rods, each having a range of angular movement with one portion adapted to effect the latching engagement between the push rod and plunger when the rocker is swung to one angular position while the plunger is retracted and another portion thereof adapted to engage a match in the receiving seat alined with the delivery seat to prevent the rocker from reaching the said latching position and to permit its latching position if the match is absent from the said receiving seat, a cam synchronized with the plunger adapted to retract the rocker from latching position after the plunger has moved forward and to permit its quick return to latching position.

after the plunger has again retracted, and spring means for maintaining engagement between the lever and cam.

13. In match packing mechanism, a safety hopper, match delivery seats therein, an intermittent conveyor, match receiving seats thereon adapted to be alined by the conveyor with the delivery seats of the hopper during a rest period of the conveyor, push rods rearwardly alined with the delivery seats and adapted to slide therealong for delivery matches therefrom to the receiving seats alined therewith, a plunger having a forward and rearward range of movement in the direction of the seats, a latch adapted to lock the rearward end of each push rod to the plunger when the plunger is retracted, rocker members for the individual push rods, each having a range of angular movement with one portion adapted to effect the latching engagement between the push rod and plunger when the rocker is swung to one angular position while the plunger is retracted and another portion thereof adapted to engage a match in the receiving seat alined with the delivery seat to prevent the rocker from reaching the said latching position and to permit its latching position if the match is absent from the said receiving seat, a cam synchronized with the plunger adapted to retract the rocker from latching position after the plunger has moved forward and to permit its quick return to latching position after the plunger has again retracted, and spring means for maintaining engagement between the lever and cam, the levers having horizontally spaced pivot supports presenting supporting surfaces to upper and lower sides of the lever, one of the supports comprising the cam and the other a stop limiting angular movement of the lever about the cam incident to the pull of the spring.

14. In match packeting mechanism, a safety hopper, match delivery seats therein, an intermittent conveyor, match receiving seats thereon adapted to align with the delivery seats of the hopper during a rest period of the conveyor, push rods rearwardly aligned with the delivery seats and adapted to slide therealong for delivering matches therefrom to the receiving seats aligned therewith, a plunger having a forward and rearward range of movement in the direction of the seats, a latch adapted to lock the rearward end of each push rod to the plunger when the plunger is retracted, rockers under the individually aligned seats, cam supports therefor, a hook upon the front end of the rocker adapted to enter the receiving seat and to engage and stop against a match whenever a match is present in the said seat during the downward movement of the hook and a latch connection between the plunger and the rearward end of the push rod effected by a rearward upward projection from the rocker whenever the rocker moves to the end of its angular movement without stopping upon a match in the receiving seat.

15. In match packeting mechanism, a safety hopper, match delivery seats therein, an intermittent conveyor, match receiving seats thereon adapted to align with the delivery seats of the hopper during a rest period of the conveyor, push rods rearwardly aligned with the delivery seats and adapted to slide therealong for delivering matches therefrom to the receiving seats aligned therewith, a plunger having a forward and rearward range of movement in the direction of the seats, a latch for each push rod adapted to lock the rearward end of the push rod to the plunger when the plunger is retracted, rocker members for the individual push rods, each having a range of angular movement with one portion adapted to effect the latching engagement between the push rod and plunger when the rocker is swung to one angular position while the plunger is retracted and another portion thereof adapted to engage a match in the receiving seat aligned with the delivery seat to prevent the rocker from reaching the said latching position and to permit its latching position if the match is absent from the said receiving seat, a cam

15. In match packing mechanism, a safety hopper, match delivery seats therein, an intermittent conveyor, match receiving seats thereon adapted to aline with the delivery seats of the hopper during a rest period of the conveyor, push rods rearwardly alined with the delivery seats and adapted to slide absent from the said receiving seat, a cam synchronized with the plunger adapted to retract the rocker from latching position after the plunger has moved forward and to permit its quick return to latching position after the plunger has again retracted, and spring means for maintaining engagement between the lever and cam, the plunger comprising

ing a flat plat normally sliding back and forth under the push rods in substantial engagement with the bottoms thereof, the forward end of the plate having a row of vertical perforations and the push rods recessed upwardly near the rearward end in registry with the perforations of the plunger when the plunger is in retracted position, a stationary plate forming the bottom of the plunger guideway and having a row of vertical guideway openings registering with the perforations of the plunger when the plunger is retracted, movable keys, normally in the guideway openings in the bottom plate and adapted 10 to pass upwardly into the plunger perforations projecting upwardly into the plunger perforations projecting upwardly into the push rod recesses to lock the plunger to the push rods, the inserted keys being prevented 20 from escape after the plunger moves somewhat forward by the top of the bottom plate.

17. In match packeting mechanism, a safety hopper, match delivery seats therein, an intermittent conveyor, match receiving seats thereon adapted to aline with the delivery seats of the hopper during a rest period of the conveyor, push rods rearwardly alined with the delivery seats and adapted to slide 25 therealong for delivering matches therefrom to the receiving seats alined therewith, a plunger having a forward and rearward range of movement in the direction of the seats, a latch for each push rod adapted to 30 lock the rearward end of the push rod to the plunger when the plunger is retracted, rocker members for the individual push rods, each having a range of angular movement with one portion adapted to effect the latching engagement between the push rod and plunger when the rocker is swung to one angular position 35 while the plunger is retracted and another portion thereof adapted to engage a match in the receiving seat alined with the delivery 40 seat to prevent the rocker from reaching the said latching position and to permit its latching position if the match is absent from the said receiving seat, a cam synchronized with the plunger adapted to retract the rocker from 45 latching position after the plunger has moved forward and to permit its quick return to latching position after the plunger has again retracted, and spring means for maintaining 50 engagement between the lever and cam, the 55 plunger comprising a flat plate normally sliding back and forth under the push rods in substantial engagement with the bottoms thereof, and a resilient latch for each push rod normally holding the push rod in its retracted position during the reciprocation of the plunger but adapted to release when the push rod is definitely locked to the plunger permitting the plunger to move the push rod along its match delivery stroke, relatching 60 when the plunger retracts the push bar.

18. In match packeting mechanism, a safety hopper, match delivery seats therein, an intermittent conveyor, match receiving seats thereon adapted to aline with the delivery seats of the hopper during a rest period of the conveyor, push rods rearwardly alined with the delivery seats and adapted to slide therealong for delivering matches therefrom to the receiving seats alined therewith, a plunger having a forward and rearward range of movement in the direction of the seats, a latch for each push rod adapted to 70 lock the rearward end of the push rod to the plunger when the plunger is retracted, rocker members for the individual push rods, each having a range of angular movement with one portion adapted to effect the latching engagement between the push rod and plunger when the rocker is swung to one angular position 75 while the plunger is retracted and another portion thereof adapted to engage a match in the receiving seat alined with the delivery seat to prevent the rocker from reaching the said latching position and to permit its latching position if the match is 80 absent from the said receiving seat, a cam synchronized with the plunger adapted to retract the rocker from latching position after the plunger has moved forward and to permit its quick return to latching position 85 after the plunger has again retracted, and spring means for maintaining engagement between the lever and cam, the plunger comprising a flat plate normally sliding back and forth under the push rods in substantial engagement with the bottoms thereof, top and bottom plates guiding the plunger and push rods, the top plate being upwardly grooved to receive the push rods and the push rods in retracted position resting at the forward 90 ends upon the bottom of the match delivery seat of the hopper and at the rearward end 95 on the plunger.

19. In a match packeting machine, a reciprocating member, a match hopper holding a plurality of matches in filling position, a plurality of individual push rods adapted to push individual matches selectively into packeting units connecting mechanism between the individual rods and the reciprocating means and means for operating the individual connections controlled by the absence of matches in a packeting unit.

20. In a match packeting mechanism, a hopper adapted to hold a number of matches in filling position, a plurality of match packeting units in line with the matches, a plurality of independent engaging mechanisms adapted to fit into the places occupied by the matches or the spaces in the units where the matches are not present, a plurality of individual match push rods corresponding in number with the mechanisms for fitting into the spaces in the match packeting units, a reciprocating member common to all of the 120 125 130

push rods and means operated by the extent
of movement of the device for fitting into the
spaces for connecting the reciprocating means
and the individual push rods whereby push
rods are actuated and matches are fed into
those spaces not completely filled by the
matches.
